By Jas. C. Nobes with
Attorney.

UNITED STATES PATENT OFFICE.

FREDERICK D. BOWES, OF SYRACUSE, NEW YORK.

DOOR LATCH.

Application filed July 21, 1925. Serial No. 44,971.

My invention relates to door latches, and it relates particularly to that type of door latch in which the latch bar is adapted to be operated from either side of the door by a thumb member.

The principal object of my invention is to provide an improved form of door latch adapted to be operated by a thumb member on either side of the door, which is so constructed and arranged that the same may be mounted in position upon the door with a minimum of labor, which is automatically adjustable to doors of varying thicknesses, and which will be simple, durable, and relatively inexpensive.

The nature and characteristic features of my invention will be more readily understood from the following description, taken in connection with the accompanying drawings forming part hereof, in which:

Figure 1 is a front elevation of a door latch embodying the main features of my present invention, the same being shown applied to the door structure;

Fig. 2 is a view, partly in side elevation and partly in section, illustrating the internal construction;

Fig. 3 is a horizontal sectional plan view of the same; and

Fig. 4 is a perspective view of one of the elements of the structure, detached.

Referring to the drawings, wherein there is shown a preferred form or embodiment of my invention, 5 is a portion of the door and 6 is the jamb. The latch bar 7 is pivoted to the door as at 8, in the usual manner, preferably extending through a guide plate 9, of a usual type, mounted on the edge of the door. Likewise, there is provided a striker plate 10 of ordinary type, mounted upon the edge of the door jamb and adapted to be engaged by the free end of the latch bar 7 in the ordinary manner.

Mounted on one side of the door is a handle 11, which is provided at its upper end with an enlarged plate portion 12 having its margins bent over so as to provide a shallow housing for a purpose to be presently explained. A thumb member 13 is pivotally mounted in an opening 14 in the plate portion 12, being positioned therein by means of shoulders 15 on the thumb member 13 in the usual manner, in which thumb members of ordinary door latches are pivoted. The inner end of the thumb member

13 comprises an extension 16, preferably U-shaped in cross-section.

A handle 17 is likewise secured on the other side of the door, and the handle 17 is also provided at its upper portion with a plate portion 18. A thumb member 19 is pivoted in an aperture 20 in the plate portion 18, by means of the shoulders 21 of the thumb member 19, and the inner end of the thumb member 19 also comprises an extension 22, also preferably U-shaped in cross-section which overlaps and normally rests upon the U-shaped extension 16 of the thumb member 13.

Mounted in the housing formed by the plate portion 12 of the handle 11 is a plate 23, which is so arranged within the housing formed by the plate portion 12 as to be vertically slidable therein. The plate member 23 is provided with a struck out extension 24, which projects through an aperture 25 in the plate portion 12 and is adapted to engage the under side of the latch bar 7. The lower portion of the plate member 23 is provided with an inwardly extending portion 26, which is also preferably U-shaped in cross-section, and overlaps the U-shaped extension 22 of the thumb member 19 and normally rests thereon. There is also preferably provided a guide plate 27, mounted within the housing formed by the plate portion 12 and the handle 11, this plate member 27 being suitably channelled so as to provide a guide for the vertical movement of the plate member 23.

The operation of the device may now be readily understood. When it is desired to operate the latch bar 7 from the side of the door upon which the handle 11 is mounted, the thumb member 13 is depressed, whereupon the inner extension 16 thereof will raise the inner extension 22 of the thumb member 19, which in turn will raise the plate member 23 by reason of the engagement of the extension 22 of the thumb member 19 with the extension 26 of the plate member 23. When the plate member 23 is raised, the outwardly projecting portion 24 thereof will, through its engagement with the under side of the latch bar 7, raise said latch bar and thereby cause the free end thereof to be lifted sufficiently to permit the same to clear the striker plate, whereby the door may then be swung open. Likewise, when it is desired to operate

the door latch from the side of the door upon which the handle 17 is mounted, the thumb member 19 is depressed, whereupon the inner extension 22 thereof will be raised, 5 causing the plate member 23 to be raised in the manner above described, thereby lifting the latch member 7.

It will be noted that the inner extensions of the respective thumb members 13 and 19, 10 as well as the inner extension of the plate 23, will readily telescope with respect to each other, whereby the structure will readily adjust itself to doors of varying thicknesses without the necessity of cutting any of the 15 parts. It will also be noted that the various parts of the device may be stamped and formed from sheet metal, whereby the expense of manufacture will be relatively small. It will still further be noted that 20 the device may be readily attached to the door with a minimum of labor, it being necessary merely to bore a single hole for the passage of the inner extensions of the thumb members and lifter plate, as no peculiarly shaped openings will be required. 25

Having thus described the nature and characteristic features of my invention, what I claim as new and desire to secure by Letters Patent is:

30 1. A door latch comprising a handle member adapted to be mounted on the side of a door, said handle member having a plate portion, a thumb member pivotally mounted in said plate portion of said handle member, said thumb member having an inwardly projecting extension, a latch bar, and a vertically slidab'e member having a projection adapted to engage the latch bar and an inwardly extending projection overlapping the extension of the thumb member whereby said slidab'e member is adapted to be actuated thereby.

45 2. A door latch comprising a handle member adapted to be mounted on the side of a door, said handle member having a plate portion, a thumb member pivotally mounted in said plate portion of said handle member, said thumb member having an inwardly projecting extension, a latch bar, and a vertically slidab'e member mounted in the plate portion of said handle member, said slidab'e member having a projection adapted to engage the latch bar and an inwardly extending projection overlapping the extension of the thumb member whereby said slidab'e member is adapted to be actuated thereby.

50 3. A door latch comprising a handle member adapted to be mounted on the side of a door, said handle member having a plate portion, a thumb member pivotally mounted in said plate portion of said handle member, said thumb member having an inwardly projecting extension, a latch bar, and a vertically slidab'e member mounted

in the plate portion of said handle member, said slidab'e member having a projection adapted to engage the latch bar and an inwardly extending projection overlapping the extension of the thumb member whereby 70 said slidab'e member is adapted to be actuated thereby, the inner extensions of said thumb member and slidab'e member being U-shaped in cross-section.

4. A door latch comprising a pair of 75 handle members adapted to be respectively mounted on each side of a door, each of said handle members having a plate portion, thumb members pivotally mounted in said plate portions of said handle members, said thumb members having inwardly projecting extensions, the extension of one of said thumb members overlapping the extension of the other thumb member, a latch bar, and a vertically slidab'e member mounted in the plate portion of one of said handle members, said slidab'e member having a projection adapted to engage the latch bar and an inwardly extending projection overlapping and adapted to be engaged by 80 the extension of one of the thumb members, the inner extensions of said thumb members and slidab'e member being U-shaped in cross-section.

5. A door latch comprising a pair of 85 handle members adapted to be respectively mounted on each side of a door, each of said handle members having a plate portion, thumb members pivotally mounted in said plate portions of said handle members, said thumb members having inwardly projecting extensions, the extension of one of said thumb members overlapping the extension of the other thumb member, a latch bar, and a vertically slidab'e member having a projection adapted to engage the latch bar and an inwardly extending projection overlapping and adapted to be engaged by 90 the extension of one of the thumb members.

6. A door latch comprising a pair of 95 handle members adapted to be respectively mounted on each side of a door, each of said handle members having a plate portion,

thumb members pivotally mounted in said plate portions of said handle members, said thumb members having inwardly projecting extensions, the extension of one of said thumb members overlapping the extension of the other thumb member, a latch bar, and a vertically slidab'e member mounted in the plate portion of one of said handle members, said slidab'e member having a projection adapted to engage the latch bar and an inwardly extending projection overlapping and adapted to be engaged by 100 the extension of one of the thumb members.

105 In testimony whereof, I have hereunto signed my name.

FREDERICK D. BOWES.
